DEVICE FOR THE RECEIPTION AND EVALUATION OF TELEGRAPH SIGNALS

Gerhard Wilhelm Kraft, Pforzheim, Germany, assignor
to International Standard Electric Corporation, New
York, N. Y., a corporation of Delaware

Application May 3, 1954, Serial No. 427,313

Claims priority, application Germany May 5, 1953

6 Claims. (Cl. 178—33)

This invention relates to printing telegraph apparatus and more particularly to improvements in or relating to a receiver of the single armature type. Devices are known which receive and evaluate telegraph signals in such a way that the signal corresponding to the received train of impulses can be recorded. There are two known methods which principally differ from each other thereby, that in the one method a receiving magnet, independently of the employed telegraph code, has a single armature, whereas in the other method one receiving magnet operates as many armatures as telegraph pulses as are employed in the code for the formation of the signal. When employing the five-unit code, and with regard to the second method, the magnet is caused to actuate five armatures. In an embodiment of the first mentioned method, the position of the armature is explored successively by means of so-called swords which are caused to occupy one of two positions. The position of these swords is translated to a receiving selector bar arrangement, which thereupon releases the corresponding code bar which causes a signal to be printed. For this operation there is required a relatively great number of components of a high precision standard, and it is essential that the quality of the material thereof be high, especially the so-called "swords." Apart therefrom it is difficult to adjust this system. Another embodiment of the single-armature-system operates in such a way that the position of the armature is explored (scanned) by levers which, in one position of the armature, are led past the armature and need not operate. In the other position of the armature they abut against the armature and are used as limiting stops for a rotating shaft on which a type-wheel is mounted. In this arrangement the levers are subjected to an unusual wear. Furthermore, single-armature-systems are known in which the position of the armature is explored by selecting levers which are each pivoted on a cam lever. By the action of a spring, these selecting levers each act upon a selecting ring which, according to the position of the armature, will be either displaced or not displaced. The selecting lever arrangement, accordingly, by the action of a spring, must perform the operation of the selecting ring control. This requires an undesirable high speed operation of the cam-coupling device and of the other components involved in the selecting ring control. The result thereof is a relatively high percentage of wear. Besides the necessary close cooperation of the components requires a high precision manufacture. The multi-armature system likewise requires a great number of components of a high precision standard, and the dependence of the components upon each other leads to difficulties in adjusting the system for operation.

The present invention aims to overcome the drawbacks

2

of the conventional arrangements. The expenditure of component parts is relatively low, and the parts to be employed require no special standard precision, because their cooperation is in no case a critical one. Accordingly, there are also required a few relatively simple adjustments. None of the component parts is subjected to excessive wear and tear. The component parts which are provided to perform the selection of the signal perform relatively simple functions, because their operations merely have a preparatory effect, whereas the principal work for setting the corresponding signal selectors is done by motor power.

The arrangement will now be particularly described with reference to the accompanying drawing, showing a preferred embodiment of the invention.

The telegraph impulses of the five-unit code assumed to be employed in this example, are received by the receiving magnet 1 having a cooperating armature 2 normally pivoted counterclockwise away from magnet 1 due to the action of the tension spring 3. The armature has an extension arm 4 which cooperates with a cam disk 5 which urges the armature clockwise in proximity to magnet 1 at a predetermined time position of each signal impulse. Another extension arm 6 of the armature is provided with a wide contacting or testing edge 7 which is wide enough to cooperate with testing teeth 8 . . . 12 of the testing levers 13 . . . 17, one tooth and testing lever being provided for each element. The testing levers 13 . . . 17 are each subject to the action of its associated tension spring 18 . . . 22, and are each controlled by a different cam 23 . . . 27, and each individually act with their contactor end portions 28 . . . 32 upon an associated setting device 33 . . . 37. These setting devices 33 . . . 37 are each arrested by an associated ratchet lever 38 . . . 42 in either of their two possible positions, which ratchet levers are normally urged against the devices 33 . . . 37 by reason of the action of an associated tension spring 43 . . . 47. Springs 43 . . . 47 normally urge levers 38 . . . 42 in a clockwise direction. Each one of the setting devices 33 . . . 37 is opposed by a cooperating exploring lever 48 . . . 52. These exploring levers 48 . . . 52 are pivoted at the upper end of a lever 53, which is normally urged by the tension spring 54 clockwise against the cam disk 55. The said exploring levers 48 . . . 52 are urged at a certain predetermined time position against the setting devices 33 . . . 37 whereby, according to their position, they meet either the upper setting arms 56 . . . 60 or the lower setting arms 61 . . . 65. By this operation, the exploring levers 48 . . . 52 are angularly turned, as indicated by the arrows. This rotary movement is transferred to the ring-type selecting bars 66 . . . 70, whereby the corresponding code signal is determined in well known manner. Together with the ring-type selecting bars 66 . . . 70 the perforating interponent levers 71 . . . 75 are selectively set by being urged to the right as the corresponding selector bar rotates counter-clockwise and according to their position will be urged upward by the common lever 76 to either actuate the perforating punches 77 . . . 81, if moved to the right and in a position beneath the punches or not. The restoring lever 82 is subject to the action of the tension spring 83 which normally urges it clockwise into cooperation with the cam 84, and serves the function of restoring the setting devices 33 . . . 37 to normal position after the selection of the signals.

Two examples will demonstrate the operation of the

devices: First it is assumed that a start or no-current signal impulse is received. The start impulse causes the armature 2 to drop off the receiving magnet 1, whereby the receiving shaft 85 will be started in the conventional manner. The first cam of the cam disk 5 will press the armature 2 via its extension 4 clockwise against the receiving magnet 1, but the armature will drop off again because the signal impulse is a currentless one. On account of this the testing edge 7 will be positioned in engagement with the testing tooth 8 of the testing lever 13, so that the testing lever 13 with its contactor portion 28 is then capable of pivoting clockwise about its lower end thereby causing its associated setting device 33 to partially rotate counterclockwise as the cam 23 rotates against the cam follower surface of lever 13 since the lower end of the lever 13 is retained by the engagement of the testing edge 7 with the tooth 8. The setting device 33 is thus moved into its second position against stop 89 in which its setting arm 56 now opposes the upper arm of its associated exploring lever 48. After the reception of all the signal impulses of a code combination the cam 55 will actuate the lever 53, which urges the upper arm of the exploring lever 48 against the setting arm 56, so that the exploring lever 48 will be caused to perform a clockwise rotary movement, thus rotating the ring-type selecting bar 66 counterclockwise into another position limited by the stops 66a which define limits of operation thereof. Shortly after, the exploring lever 48 is withdrawn from the setting arm 56 and the restoring lever 82 is actuated counterclockwise by the cam 84, whereby the setting device 33 will be rotated clockwise and restored to its first stop position.

In the second example it will be assumed that a mark or current signal impulse is received.

The start or space signal, in the manner described above, causes the shaft 85 to start rotation and the first cam of the cam disk 5 urges the armature 2 against the receiving magnet 1 by reason of the clockwise movement of extension 4 as it rides on the said cam surface. Since the next impulse will be a mark or current-carrying one, the armature 2 will remain attracted, whereby the testing edge 7 will be disengaged from the testing tooth 8. When now the cam 23 rides over the testing lever 13, the latter will find no pivot support at its testing tooth 8 upon which to pivot in a clockwise direction. However, the lever will find a counter support at its upper end by means of its contactor portion 28 resting against a depending arm on the setting device 33, so that the testing lever 13 will pivot about 28 in a counterclockwise direction against the tension of its spring 18, but without moving the setting device 33. This movement of the lever 13 is possible on account of the engagement of the bearing pin 86 in a slot at the lower end of lever 13. The spring 18 will restore the lever 13 to normal when the cam 23 passes the camming surface on lever 13, so as to be ready for selecting the next succeeding signal. Hence the setting device 33 will remain in the position shown. As described in the first example, the exploring lever 48 performs a testing of the position of the setting device 33 and will, accordingly, in this case engage the lower arm 61 of the setting device 33, thereby actuating the selecting ring 66 to the position shown in the drawing. The restoring lever 82 will now perform its counterclockwise movement, but does not actuate the setting device 33 because it has not changed its position. The limiting stops 87 and 89 serve to prevent any rotary movement of the setting devices 33 . . . 37 when being explored by the exploring levers 48 . . . 52, so that the ratchet levers 38 . . . 42 need only retain the setting devices in either of their two operable positions. The limiting stop 88 prevents the testing levers 13 . . . 17 and the restoring lever 82 from following the trough portion of their respective cams.

It will be understood that if a seven unit code is to be used, there will be required seven testing levers, and a

like number of cams, setting devices, exploring devices, selector bars, etc.

While I have described above the principles of my invention in connection with specific apparatus, it is to be clearly understood that this description is made only by way of example and not as a limitation to the scope of my invention as set forth in the objects thereof and in the accompanying claims.

What is claimed is:

1. In a start-stop teleprinter receiver a rotatable control shaft, a receiver magnet, an armature for said electromagnet, means under control of said shaft for periodically moving said armature in proximity to said magnet independent of the nature of the received signal, a plurality of cams coupled to said shaft, a plurality of testing levers, one for each element of the telegraph code to be received, each adapted to cooperate with a different one of said cams, a plurality rockable setting devices, each adapted to be rocked from a first position to a second position by a different one of said testing levers, a plurality of exploring levers each associated with a different one of said setting devices, a plurality of selector means, each associated with a different one of said exploring levers, common means under control of another one of said cams for periodically moving each of said exploring levers against its associated setting device, each of said exploring levers adapted to be set in one of two angular positions dependent upon the rocked position of its associated setting device, each of said selector means adapted to be set in either of two angular positions upon movement of said common means, means under control of another one of said cams for restoring each of said setting devices from its second position to its first position after said common means has moved said exploring levers, and detent means coupled to said armature for selectively rendering the motion imparted to said testing levers by their associated cams effective or ineffective to rock said setting devices from their first position to their second position dependent upon the respective state of deenergization or energization of said magnet.
2. In a start-stop teleprinter receiver as claimed in claim 1 wherein said selector means comprise a plurality of ring type selector bars, said bars adapted to be angularly rotated under control of said exploring levers.
3. In a start-stop teleprinter receiver as claimed in claim 1, further comprising means for retaining each of said setting devices in either of their two cooperative positions when not cooperating with their associated testing levers.
4. In a start-stop teleprinter receiver as claimed in claim 1, further comprising a single stop against which said restoring means and said testing levers are adapted to abut when not being actuated by their respective associated cams.
5. In a start-stop teleprinter receiver as claimed in claim 1, wherein each of said testing levers comprises a pivot, an arcuate shaped member having a cam following surface on the inside of its arc, a first pivoting portion adjacent a first end of said member and a second pivoting portion at the opposite end of said member, spring means adapted to normally urge said member against said pivot, and a latch surface at the first end of said member adapted to cooperate with said means coupled to said armature for selectively rendering ineffective the motion imparted to said members by said cams.
6. In a start-stop teleprinter as claimed in claim 3, wherein each of said setting devices comprises a multi-toothed member, one of said testing levers and said restoring means adapted to be interposed between a first pair of said teeth, a second pair of said teeth, of which each tooth is adapted to coact with a different portion of an exploring lever, and a plurality of additional teeth, said additional teeth adapted to cooperate with said retaining means.
